(57) **CLAIM**

The ornamental design for a utility bucket with wheels and handle, as shown and described.

DESCRIPTION

FIG. 1 is a rear perspective view of the utility bucket with wheels and handle of the present invention, with the handle in a fully extended position;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a rear elevation view thereof, with the handle in compressed position; and,

FIG. 9 is a right side elevation view thereof, with the handle in compressed position; the left side elevation view being a mirror image thereof.
